UNITED STATES PATENT OFFICE

143,029

DESIGN FOR A HOIST CONTROL UNIT

Harvey W. Rockwell, Cedar Rapids, Iowa, assignor to Lapland-Choate Manufacturing Co. Inc., Cedar Rapids, Iowa, a corporation of Iowa

Application January 20, 1945, Serial No. 117,519

Term of patent 7 years

(Cl. D41—1)

To all whom it may concern:

Be it known that I, Harvey W. Rockwell, a citizen of the United States and a resident of Cedar Rapids, in the county of Linn and State of Iowa, have invented a new, original, and ornamental Design for a Hoist Control Unit, of which the following is a specification, reference being had to the accompanying drawing forming part thereof.

Figure 1 is a top plan view of a hoist control unit showing my new design.

Figure 2 is a rear elevational view thereof.

Figure 3 is a side elevational view thereof, and Figure 4 is a front elevational view thereof.

I claim:

The ornamental design for a hoist control unit, substantially as shown.

HARVEY W. ROCKWELL.
